US0D1071904S

(12) **United States Design Patent** (10) Patent No.: **US D1,071,904 S**
(45) Date of Patent: ** Apr. 22, 2025

(54) **MULTI-EFFECTS PROCESSOR**

(71) Applicant: **Fender Musical Instruments Corporation**, Los Angeles, CA (US)

(72) Inventors: **James Matisán Gifford**, Tempe, AZ (US); **Kevin Bradley Reddy**, Tacoma, WA (US); **Henry Wong**, Tempe, AZ (US); **Max Michael Gutnik**, Newbury Park, CA (US); **Kenneth William Porter**, Scottsdale, AZ (US)

(73) Assignee: **Fender Musical Instruments Corporation**, Los Angeles, CA (US)

(**) Term: **15 Years**

(21) Appl. No.: **29/911,996**

(22) Filed: **Sep. 12, 2023**

(51) LOC (15) Cl. **14-03**

CLAIM

The ornamental design for a multi-effects processor as shown and described.

DESCRIPTION

FIG. 1 is a front perspective view of a multi-effects processor showing our new design;
FIG. 2 is a front view thereof;
FIG. 3 is a rear view thereof;
FIG. 4 is side view thereof;
FIG. 5 is a side view of the opposite side of FIG. 4;
FIG. 6 is a top view thereof; and,
FIG. 7 is a bottom view thereof.

(Continued)

The broken lines shown in the drawings illustrate portions of a multi-effects processor that form no part of the claimed design.
